CLYDE E. BROWN, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS

WEFT DETECTING MECHANISM FOR DROP BOX LOOMS

Application filed April 17, 1931. Serial No. 530,900.

This invention relates to looms in which drop boxes are provided at the detecting side of the loom and in which a separate weft detector is definitely associated with each drop box and moves upward and downward therewith.

It is the general object of my invention to provide improved means for determining which weft detector shall become operative at a given time and which detector shall remain inoperative.

More specifically, I provide a construction by which the detector associated with the shuttle about to become active will be left free for detecting action, while the other detector will be positively withdrawn or otherwise held inoperative.

My invention also relates to an improved construction in the supporting slide of a weft detector, so designed that a certain amount of lost motion is provided for a purpose to be described.

My invention further relates to arrangements and combinations of parts which will be hereinafter described and more particularly pointed out in the appended claims.

A preferred form of the invention is shown in the drawing, in which

Fig. 1 is an end elevation, partly in section, showing portions of a drop box loom having my improvements applied thereto;

Fig. 2 is a front elevation of the detecting mechanism, looking in the direction of the arrow 2 in Fig. 1;

Fig. 3 is a sectional plan view, taken along the line 3—3 in Fig. 2, and

Figs. 4 and 5 are diagrammatic views indicating the operation of certain parts under different conditions.

Referring to the drawing, I have shown portions of a loom frame 10, a lay 11, a lay end 12, drop boxes 13 vertically movable thereon, and a lifter rod 14 for raising and lowering the boxes, these parts being of any usual construction.

A detector slide 20 is mounted in a vertical guideway in a support 21, secured in fixed position to the loom frame 10. Weft detecting devices A and B are mounted in spaced relation on arms 23 and 24 projecting laterally

from the slide 20. The vertical spacing of the detecting devices A and B corresponds to the vertical spacing of the drop boxes 13 and of the shuttles S and S' boxed therein.

Each weft detecting device comprises a detecting member 30 pivoted at 31 (Fig. 3) to a member 34 which is associated with a similar member 35 to form a sliding support for the detector 30. The members 34 and 35 are slideable in a guideway in a stand 36 and each member is cut away or recessed as indicated at 37 and is provided with a lug or projection 38, said lugs and recesses permitting a predetermined amount of lost motion between the slide members 34 and 35.

A spring 40 in each stand 36 engages the detector 30 at the point 41 and holds a forwardly extending portion 42 of the detector against a stop pin 43 on the slide member 34. The single spring 40 also acts to separate the slide members 34 and 35 to their fullest extent and to maintain the rear slide member 34 and the detector 30 normally in extreme rearward position.

The detector 30 of each detecting device A or B engages a vertically elongated contact member 50, preferably formed as an open wire frame work pivoted in bearings 51 and 52 on the side of the stand 21. An arm 53 is secured to the axial portion of the contact member 50 and extends adjacent the path of movement of a floating lever or chopper 55.

When a detector engages a weft carrier having a sufficient supply of weft thereon, the detector is moved directly forward, sliding past the contact member 50 without communicating any motion thereto. When the weft is substantially exhausted, however, the detector 30 slides along the surface of the carrier to the left in Fig. 3, communicating motion to the contact member 50 and swinging the arm 53 into the path of the floating lever or chopper 55, by which action the lever 55 is rendered operative to initiate weft replenishment in the usual manner.

The detector slide 20 is provided with a stud 60 positioned in an arcuate slot 61 in the front end of an arm 63, the stud 60 entering the slot 61 as the lay approaches front center. The slide 20 is provided with notches or

depressions 64 (Fig. 2) adapted to receive the pointed end of a spring-pressed plunger 65 and is thereby retained in desired vertical position when the lay moves rearward and the stud 60 is free from the slot 61 in the positioning arm 63.

Upper and lower shields 70 and 71 are pivoted at 72 and 73 on the fixed stand or support 21. Each shield 70 or 71 is provided with a guiding portion or flange 75, adapted to cooperate with offset lugs 76 (Figs. 2 and 3) at the front end of the slide members 34 and 35. Springs 77 hold the free ends of the shield members 70 and 71 pressed against the side of the support 21, as indicated in Fig. 1. The flanges 75 are cut away at their extreme end portions so that the lugs 76 may pass by the flanges at their upper or lower limits of travel, as will be hereinafter described.

The operation of my invention is as follows:

Weft replenishment in this type of loom commonly occurs at the opposite side of the loom from the detection of weft exhaustion. In order that replenishment may take place in the indicated exhausted shuttle, it is desirable that the detecting mechanism operate only with the shuttle about to become active and not with the shuttle which is moving to inactive position.

Weft detection takes place as the boxes are approaching front center, at which time the shuttle about to become active is moving upward or downward toward active position in alignment with the shuttle race, and the shuttle about to become inactive is moving upward or downward away from such alignment.

In Fig. 1 the boxes and detecting devices A and B are shown in an intermediate position, neither shuttle being in active position. I have indicated in dotted lines at 76^b in Fig. 1 the position which would be occupied by the lug or projection 76 of the detecting device B at the completion of an operative upward movement, and at 76^a I have shown the corresponding position of the detecting device A after an inoperative upward movement.

Assuming that a downward change in the position of the shuttles and drop boxes then takes place, bringing the upper shuttle S to active position the slide 20 will be simultaneously lowered, carrying the upper and lower lugs or projections 76 downward relative to the shields 70 and 71. The effect of this downward movement is indicated in Fig. 4, the upper lug or projection 76^a moving directly downward behind the flange 75 of the upper shield 70 while the lower lug or projection 76^b is engaged by the flange 75 of the lower shield 71 and is drawn outward and forward, withdrawing the lower detector 30 of the detecting device B from engagement

with the weft carrier W, as indicated in Fig. 1.

In other words, as the upper shuttle S moves downward to active position, the corresponding weft detector 30 is permitted to operate and as the lower shuttle S' moves to downward inoperative position, the corresponding weft detector is drawn forward and rendered inoperative by the action of the shield 71. This movement of the lugs 76 is shown diagrammatically in Fig. 4.

If the boxes are in lowered position, with the shuttle S at the level of the shuttle race and the shuttle S' about to be raised and become active, the upper detector 30 will be withdrawn by the upper shield 70, while the lug 76 of the lower detector will pass behind the shield 71, leaving the lower detector 30 free and operative, as indicated in Fig. 5. As the detector devices A and B complete their upward or downward movement, the lugs 76 are freed from the cut-away end portions of the flanges 75.

I have formed the detector slide in two parts 34 and 35 so that the rear part 34 may move forward when the associated detector 30 engages a full bobbin without causing the portion 35 of the slide to be pushed forward and engage the under side of the corresponding shield 70 or 71, as such engagement would add the tension of the corresponding spring 77 to the force of the spring 40, causing an unnecessarily strong pressure of the detector 30 against the weft on the bobbin.

Having thus described my invention, it will be seen that I have provided a quite simple construction by which the detector moving from active position is rendered inoperative and the detector moving toward active position is rendered operative.

The device is thus adapted for use in a loom designed for mixing filling, or in any other loom, in which the boxes and shuttles are shifted after each pick.

Having thus described my invention and the advantages thereof, I do not wish to be limited to the details herein disclosed, otherwise than as set forth in the claims, but what I claim is:—

1. In a weft replenishing drop box loom having a pair of shuttle boxes and means to move said boxes to bring a selected shuttle to active position, a weft detecting device definitely associated with each shuttle box, and means to render each detecting device inoperative as its associated shuttle box is moved to inactive position and to restore said detecting device to operative condition as the movement of the shuttle box to inactive position is completed.

2. In a weft replenishing drop box loom having a pair of shuttle boxes and means to move said boxes to bring a selected shuttle to active position, a weft detecting device definitely associated with each shuttle box,

and means to render each detecting device inoperative as its associated shuttle box is moved to inactive position, said means leaving freely operative at all times the detecting device associated with the shuttle box moving to active position and restoring the inoperative detecting device to operative condition as the shuttle box movement is completed.

5 3. In a weft replenishing drop box loom having a pair of shuttle boxes and means to move said boxes to bring a selected shuttle to active position, a weft detecting device definitely associated with each shuttle box, 10 and a separately movable detector-withdrawing element associated with each detecting device and effective to render its detecting device inoperative as said device and its associated shuttle box are moved to inactive position said withdrawing elements being both inoperative with respect to a shuttle box and associated detector moving toward active position.

4. The combination in a drop box loom as 25 set forth in claim 3, in which each detecting device has a portion cooperating with its associated control element only and engaged by said control element as said detecting device is moved from active to inactive position.

5. The combination in a drop box loom as set forth in claim 3, in which each detecting device has a portion cooperating with its associated control element only and engaged by 35 said control element as said detecting device is moved from mid-position to extreme position relative to said control elements.

6. The combination in a drop box loom as set forth in claim 3, in which each detecting device has a portion cooperating with its associated control element only and engaged by 40 said control element as said detecting device is moved from active to inactive position, but said engaging portion being free from said control element on the return movement of the associated detecting device to inactive position.

7. In a weft replenishing drop box loom having a pair of shuttle boxes and means to move said boxes to bring a selected shuttle to active position, a weft detecting device definitely associated with each shuttle box, and means to withdraw each detecting device from weft-engaging position as said device 55 and its associated shuttle box is moved to inactive position, said means comprising shields having flanges of limited length thereon and each detecting device having a projecting portion riding on one of said flanges as said detecting device moves to inactive position and passing off of an end of said flange as the device reaches inactive position.

8. The combination in a drop box loom as set forth in claim 7, in which said project-

ing portion passes under said flange as said detecting device is moved to active position and passes beyond the second end of said flange as said device reaches active position.

9. In a loom, a weft detecting device comprising a detector, a stand, a slide guided in said stand and to which said detector is pivoted, said slide comprising front and rear portions and having a slip-joint connection between said portions permitting limited lost motion of said portions relative to each other, and a device engageable with said front portion to positively withdraw said detector from weft-engaging position.

In testimony whereof I have hereunto affixed my signature.
